UNITED STATES PATENT OFFICE.

SAMUEL F. BURDETT AND JOHN BRADLEY, OF CHELMSFORD, MASSACHUSETTS, ASSIGNORS TO THE BYFIELD MANUFACTURING COMPANY, OF SAME PLACE.

CIRCULAR-KNITTING MACHINE.

SPECIFICATION forming part of Letters Patent No. 442,168, dated December 9, 1890.

Application filed November 25, 1889, Serial No. 331,444. (No model.)

To all whom it may concern:

Be it known that we, SAMUEL F. BURDETT and JOHN BRADLEY, of Chelmsford, in the county of Middlesex and State of Massachusetts, have invented certain new and useful Improvements in Circular-Knitting Machines, of which the following is a specification.

Our improvements have relation to knitting-machines employing a plurality of yarn-guides which are adapted to be thrown into and out of operation for the purpose of producing striped fabrics.

It is the object of the invention to provide improved means whereby when a tubular fabric of sufficient length to produce a single stocking has been knit the line of "joinings"—that is, the line along which the yarns are brought into and thrown out of operation—may be changed to the opposite side of the web and the pattern reproduced in reverse order in a tubular fabric of the same length, so that when the said lengths of the said fabric are made into a pair of stockings the patterns or figures will "match," and the joinings in each stocking will be on a line down the back of the leg, where, if it shows at all, it will have the least marring effect.

It is also the object of the invention to provide improved means for controlling the operation of the pattern device which throws the yarn-guides into and out of operation, so that a long pattern may be knit with a comparatively small pattern device.

It is also the object of the invention to produce other improvements in knitting-machines for making striped fabrics, incidental to the foregoing.

Reference is to be had to the annexed drawings and the letters of reference marked thereon, forming a part of this specification, the same letters designating the same parts or features, as the case may be, wherever they occur.

Of the drawings, Figure 1 is a top view of a spring-beard-needle knitting-machine equipped with our invention. Fig. 2 is a side elevation, looking from the pattern device toward the "head" or cylinder. Fig. 3 is also a side elevation, a part being shown in section, parts being broken away, and the

head or cylinder being represented as nearly naked, the view being taken from a point which fully shows the pattern device, yarn-guides, and needle cylinder or head. Fig. 4 is a diagram in top plan showing the two cams on the needle-head and the means directly actuated thereby for the purpose of operating the pattern device, and showing, also, to a certain extent the means whereby the shifting of the joinings in the fabric is effected. Figs. 5 and 6 are diagrams in plan, and partly in section, showing the means beneath what is shown in Fig. 4 for operating and controlling the operations of the pattern device. Fig. 7 is a side view of a portion of the ratcheted double-worm pattern-cylinder and some of its connections. Fig. 8 is a horizontal sectional view of the said cylinder and the shaft upon which it is adapted to slide. Fig. 9 is a similar view showing the traveler for traversing the pattern-cylinder upon its shaft, as also the means by which the traveler is supported. Fig. 10 is a bottom plan view of the pattern-disk and an associated part. Fig. 11 is a section of the pattern-disk.

In the drawings, *a* designates the needle-head, *b* the needles, *c* the yarn-guides, *d* the stitch-wheel, *e* the dividing-wheel, *f* the presser-wheel, *g* the landing-wheel, *h* the knocking-over wheel, *i* the auxiliary-wheel, *j* the clearing-wheel, *k* the push-back, *l* the "end" guard or guide, *m* the yarn-holding device, and *n* the yarn-severing device, of a circular spring-beard-needle knitting-machine to which we have applied our jointly-wrought improvements.

The yarn-holding device consists of a swinging weighted block adapted normally to rest upon a plate, under which block and upon which plate the ends of the yarn are drawn and held after they are thrown out of action, and the yarn-severing device consists of a rotating disk attached to the side of the dividing-wheel, said disk having a sharp periphery, against which the yarns are drawn and by which they are cut in the operation of throwing them out of action. These devices, however, are not herein claimed, since they do not form a part of our joint invention.

As shown, the knitting-head *a* is provided with two cams *o* *p*, one arranged on the opposite side of the head from the other, and the cam *o* being arranged at a higher horizontal plane than the cam *p*.

The yarn-guides *c* are fulcrumed on a bracket *q*, their heels *r* resting upon the pattern-disk *s*, and held down thereon by the springs *t* in a manner that will be understood by an inspection of Fig. 3 of the drawings. In the face of the pattern-disk *s* on lines or paths intersecting the heels *r* of the yarn-guides the pattern-disk is provided with holes, in which may be arranged pins *u*, adapted to engage the heels of the yarn-guides, raising the same, and so throwing the forward end of the guide down, carrying its yarn into action, it being understood that when the heel of a yarn-guide rides on the surface of the pattern-disk the forward end of such guide will be raised and its yarn carried or held out of action. The pattern-disk *s* is provided on its periphery with ratchet-teeth, with which a pawl *v* is adapted to engage, said pawl being pivoted on the end of a lever *w*, and held pressed toward the teeth of the ratchet-wheel by means of a spring *x*. The lever *w* is provided on its inner end with a hub, whereby it is fulcrumed on a stud *y*. To the upper end or face of the said hub there is secured an extension-piece *z*, having a slot *a'* formed therein, through which slot a pin *b'* extends from the lever *c'*, which latter lever is secured to a sleeve *d'* on the vertical shaft *d*'. The connection of the hub of lever *w* with fulcrum-stud *y* is such as to permit the lever to be oscillated in a horizontal line and yet allow its outer or free end to be slightly raised and lowered. In the present instance the lever is simply loosely fulcrumed on the stud *y*, so that it may be moved vertically at its free end, as described. Various means may, however, be provided to secure the vertical movement of the free end of the lever with the oscillating movement on its fulcrum-stud. Connected at one end with the lever *w* is a bar or lever *e'*, the free end of which extends out so as to be engaged and actuated by the cams *o* and *p* on the head *a*. The pattern-disk is provided on its under face (see Fig. 10) with a cam-segment *f'*, extending half-way therearound, which cam-segment is constructed and arranged to act on one end of a lever *g'*, fulcrumed on a stud *h'*, the other end of said lever *g'* extending under the bar *e'* forward of the point where it is connected to the lever *w*. With this construction when the inner end of the lever *g'* bears on the cam-segment *f'* the forward end of the said lever will be raised, raising the free end of bar *e'* into the path of travel of cam *o* on the head *a*, and when the inner end of the lever *g'* rests on the under face of the pattern-disk *s* the outer end of the said lever will be depressed, allowing the free end of the bar *e'* to drop into the path of travel of the cam *p*.

It will be obvious to those skilled in the art

that when the bar *e'* is so placed as to be actuated by the cam *o* it will operate the yarn-guides, so as to throw the same into and out of action at a point in the circle of needles opposite that at which the yarn-guides will be in like manner operated when the bar *e'* is actuated by the cam *p*, which latter cam is arranged on the cylinder at a point opposite the cam *o*. Hence by this change in the operation of the bar *e'* the line of the joinings of the yarns in the fabric will be changed from one side to the other.

i' designates a cylinder arranged to rotate 80 and move longitudinally on a vertical shaft *j'*. The said cylinder is provided with a double or compound worm *v*, in which is arranged a traveler *k'*, swiveled in a collar *l'*, secured to a vertical shaft *o'*. With this construction and arrangement of parts when the pattern-cylinder *i'* is rotated, as in practice it is, the traveler *k'*, traversing the worm or groove, as shown in Fig. 2, will gradually raise the said cylinder until the traveler 90 reaches the bottom thereof, as shown in Fig. 7, when the traveler will be automatically shifted, so as to travel in the opposite direction in the worm-groove and so lower the said pattern-cylinder.

The operation of the cam *o* or *p* on the bar *e'* will effect the vibration of lever *w*, its extension *z* and lever *c'*, resulting in the oscillation of the sleeve *d'* on the shaft *d*', with which sleeve pawl-arm *n'* is connected. The free end of arm *n'* is provided with a spring-pressed pawl *m'*, which engages the teeth formed on the outer surface or periphery of the pattern-cylinder *i'*, resulting as the arm *n'* is vibrated in a step-by-step rotation of the 105 said cylinder.

o' is a vertical shaft, upon which shaft there is fulcrumed an arm or lever *p'*, provided on one end with a pin *q'*, extending up behind the pawl *v*, arranged to actuate the pattern-disk *s*.

The collar *l'* has a dog *r'* pivoted upon it, the free end of which dog extends into the worm-groove of the pattern-cylinder *i'* in such position as to be engaged and moved by the 115 pattern-pins *t'*, arranged in holes *s'*, formed in the said worm-groove. When one of the said pins engages the free end of the dog *r'*, it will move the said dog in the direction of arrow 1, carrying the lug *u'*, against which 120 the dog bears, in the same direction. The lug *u'* is secured to the sleeve *v'* on shaft *w'*, to the upper end of which sleeve is secured an arm *x'*, provided on its free end with a pin *y'*, extending up behind a pin *z'* projecting inwardly from the adjacent end of arm or lever *p'*. When the dog *r'* moves lug *u'* in the direction of arrow 1, arm *x'* will be moved in the direction of arrow 2 marked thereon, and the pin *y'*, acting on the pin *z'*, will move the 130 opposite end of arm *p'* in the direction of arrow 3, allowing pawl *v* to engage the teeth of ratchet-disk *s*, and when the dog *r'* rides on the bottom of the worm-grooves the several

parts will be moved by spring p^3 , connected at one end with the said lever p' and at the other end with a stationary part of the machine, in a direction opposite to the flight of the arrows, and so cause pin q' to carry pawl r out of engagement with the teeth of the pattern-disk. By carrying pawl r from time to time out of engagement with the ratchet-teeth of the pattern-disk s the latter can be made comparatively small and yet effect the knitting of a varied pattern in quite a long web.

The construction, arrangement, and timing of parts are such that a web sufficiently long for a stocking may be knit in one-half of a revolution of the pattern-disk s , during which time the traveler k' may have traversed the worm-groove of the pattern-cylinder i' from end to end thereof, so that the said traveler will begin its return in the worm-groove the moment that bar e' is changed from contact with one cam on the needle-cylinder to the other, thus reproducing the pattern in reverse order and changing the line of joining of the stripping-threads from one side of the tubular web to the other.

Various changes may be made in the form and arrangement of parts comprising our improvements without departing from the nature or spirit thereof.

Having thus explained the nature of our improvements and described a way of constructing and using the same, we declare that what we claim is—

1. The combination, with the needle-cylinder and the two cams thereon arranged in different horizontal planes, of a pattern-plate, actuating mechanism therefor, and a bar e' for actuating the said pattern-plate-actuating mechanism, movable into the path of either of said cams, as set forth.

2. The combination, with the needle-cylinder and the two cams thereon arranged in different horizontal planes, of a pattern-plate, a lever and pawl for actuating the said pattern-plate, a bar connected to the said lever and movable into the path of either of the said cams, a cam on the pattern-plate, and a pivoted lever arranged to be actuated by the cam on the pattern-plate and to move the connected bar from the path of travel of one cam on the needle-cylinder to another, as set forth. 45

3. A pattern device for knitting and cognate machines, consisting of a cylinder having a double or compound worm-groove formed in its face and provided with ratchet-teeth, whereby it may be turned, and pattern-pins in the said groove, as set forth. 50

4. A pattern mechanism for knitting and cognate machines, consisting of a cylinder having a double or compound worm-groove formed in its face and provided with ratchet-teeth, whereby it may be turned, and pattern-pins in the said groove, in combination with a shaft upon which the said cylinder is adapted to turn and move longitudinally, a reciprocating pawl engaging said ratchet-teeth to rotate the said cylinder, and a swiveled traveler arranged on a stationary support and adapted to operate in the said worm-groove, 65 as set forth. 70

In testimony whereof we have signed our names to this specification, in the presence of two subscribing witnesses, this 12th day of November, A. D. 1889.
